(57) **CLAIM**

The ornamental design for an ID tag reading write-in gate, as shown and described.

DESCRIPTION

FIG. 1 is a front view showing my new design for an ID tag reading write-in gate;

FIG. 2 is a side view of the ID tag reading write-in gate of FIG. 1;

FIG. 3 is a top view of the ID tag reading write-in gate of FIG. 1;

FIG. 4 is a bottom view of the ID tag reading write-in gate of FIG. 1;

FIG. 5 is a perspective view of the ID tag reading write-in gate of FIG. 1; and,

FIG. 6 is a cross-sectional view of the ID tag reading write-in gate of FIG. 1 taken along line VI—VI of FIG. 3.
